UNITED STATES PATENT OFFICE.

WALTER MUELBERGER, OF MAPLEWOOD, NEW JERSEY, ASSIGNOR TO NATHAN & COHEN CO. INC., OF NEW YORK, N. Y., A CORPORATION OF NEW YORK.

DESIGN FOR A TEXTILE FABRIC.

Application filed April 9, 1928. Serial No. 26,199. Term of patent 3½ years.

To all whom it may concern:

Be it known that I, WALTER MUELBERGER, a citizen of the United States, residing at Maplewood, county of Essex, State of New Jersey, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric substantially as shown.

WALTER MUELBERGER.
